UNITED STATES PATENT OFFICE.

CONRAD H. KLEE, OF HONESDALE, PENNSYLVANIA.

GLOBE FAUCET OR VALVE.

1,064,660.

Specification of Letters Patent. Patented June 10, 1913.

Application filed January 15, 1913. Serial No. 742,116.

To all whom it may concern:

Be it known that I, CONRAD H. KLEE, a citizen of the United States, residing at Honesdale, in the county of Wayne and State of Pennsylvania, have invented a new and useful Globe Faucet or Valve; and I do hereby declare the following to be a full, clear, and exact description of the invention, such as will enable others skilled in the art to which it appertains to make and use the same.

This invention relates to a new and useful globe faucet or valve.

As an object of the invention, it is the aim to provide an improved faucet in which a downwardly depending partition is omitted, which partition in other forms of faucets cause a resistance to the flow of fluid or water, as well as causing the faucet casing to choke or clog up with sediment. To overcome the resistance to a very great extent, and to eliminate the choking or clogging up of the casing, it will be seen that the casing is provided with an upwardly curved unobstructed passage adjacent the entrance end of the casing. It will also be noted that adjacent the outlet end of the faucet a similar unobstructed curved passage is provided.

Another feature of the invention is the centrally arranged wall rising from the lower wall of the valve casing up to and substantially in alignment with the upper portion of the horizontal part of the casing, which together with a part of the upper horizontal portion of the casing forms a valve seat.

Another object of the invention is the provision of a valve stem having a loosely or flexibly connected valve at its lower end to coöperate with the valve seat.

The object in providing the improved flexibly or loosely connected valve is to allow the fluid to hold the valve securely closed, when the same is resting loosely upon the valve seat, and to allow the hard rubber packing of the valve to accommodate itself to the unevennesses of the valve seat, when the valve is completely closed by the operation of the stem.

Another feature of the invention is the practical desirable and improved manner in which the hard rubber packing of the valve is embedded in place.

There are disclosed in the drawings certain features of construction, but in practice

tical fields these features may necessitate alterations, to which the patentee is entitled, provided the alterations fall within the scope of what is claimed.

The invention comprises further features and combination of parts, as hereinafter set forth, shown in the drawings and claimed.

In the drawings: Figure 1 is a sectional view through the improved globe faucet or valve, showing the same constructed in accordance with the invention. Fig. 2 is an enlarged detail sectional view of the flexibly connected valve of the stem.

Referring more particularly to the drawings 1 designates a casing of the improved faucet, said casing having an inlet end and an outlet end, and provided with an upwardly extending wall upon the interior rising from the lower portion of the casing. This wall 3 extends upwardly to a point substantially in a line with the upper horizontal portion of the casing, as indicated by the dotted line 4. The opposite side portions 6 and 7 of the wall gradually curve or merge into the lower interior surface of the horizontal portion of the casing, so that the fluid through the inlet 9 and through the outlet 10 will pass over a smooth surface in passing over the wall. The upper portion of the wall 3 is provided with a rib 11, which together with the rib 12 of the upper portion 13 of the horizontal part 8 of the valve casing forms an improved valve seat, with which the valve 14 co-operates. The upper portion of the wall 3 adjacent the rib 11 is provided with a goose neck lip 15, rising above and inclined toward the valve seat, so as to cause the flow of water or other fluid to press upon the upper surface 16 of the valve 14, in order to hold the same securely closed.

The globe extension 17 of the casing is interiorly threaded at 18, with which the casing 19 is connected. The valve stem 20 passes through the casing 19 and through a packing gland 21, which is formed by the nut 22, which is threaded to the casing 19, there being an annular plate included in the packing gland in engagement with the packing. This annular plate 23 has an annular flange 24, which extends between the nut and the valve stem. The valve stem is provided with the usual hand wheel 25 whereby the stem may be rotated, in

order to raise and lower the same relative to the casing 19, into which the stem is threaded, as shown at 26.

The valve 14 is constructed in the form 5 of a disk member having an upwardly extending annular flange 28, the inner surface of which is threaded, to be engaged by the threaded portion 29 of the nut 30, between which and the disk valve the enlargement 31 10 of the valve stem is interposed, thereby not only swivelly connecting the valve disk to the stem, but also loosely or flexibly connecting the valve disk, so that the fluid in passing through the inlet portion of the casing 15 will hold the valve closed, provided the same is loosely resting upon the valve seat.

The outer peripheral portion of the valve disk is constructed with a downwardly extending flange 32, and engaging within this 20 flange is a hard rubber packing disk 33, the same being held in place by the nut 34, which is threaded to an extension 35 (which passes through an opening 36 in the hard rubber packing disk) of the valve disk. By 25 rotating the hand wheel, the valve stem is correspondingly rotated, which will cause the valve to seat or unseat, thereby controlling the fluid or water in its flow.

From the foregoing it will be noted that 30 there has been devised a simple and efficient

globe faucet or valve, and one which has been found practical, owing to its unobstructed smooth inlet and outlet passages.

The invention having been set forth, what is claimed as new and useful is:—

1. In a globe faucet, a casing having an inlet and a discharge passage merging together in communication, a valve seat located substantially at the point of communication, the inlet passage terminating in a 40 lip adjacent to and rising above and inclined toward the valve seat, and a valve member to coöperate with said seat.

2. In a globe faucet, a casing having inlet and discharge passages, a valve seat located 45 substantially at the junction of the two passages, the inlet passage being contracted adjacent to and above the valve seat, the inlet passage terminating in a goose neck lip at the contracted portion of the passage adjacent to and rising above and inclined toward the valve seat, and a valve member coöperating with said seat.

In testimony whereof I have signed my name to this specification in the presence of 50 two subscribing witnesses.

CONRAD H. KLEE.
